[57] CLAIM

The ornamental design for an exophthalmometer, as shown and described.

DESCRIPTION

FIG. 1 is a perspective view of an exophthalmometer showing my new design;

FIG. 2 is a front elevational view;

FIG. 3 is an enlarged detail view of the top right portion of the claimed design, with portions being eliminated for ease of illustration;

FIG. 4 is a rear elevational view;

FIG. 5 is a top plan view;

FIG. 6 is a bottom plan view; and,

FIG. 7 is a cross-sectional view taken along line 7—7 of FIG. 1.
